2,790,005
PREPARATION OF CIVETONE AND ITS
HOMOLOGS

Alfred T. Blomquist, and Joseph Wolinsky, Ithaca, N. Y.

No Drawing. Application December 9, 1955,
Serial No. 552,228

6 Claims. (Cl. 260—586)

This invention relates to the production of chemicals and in particular to the production of large-ring or macrocyclic monoketones. 15

A principal object of the present invention is to provide a process for the production of homologs of civetone from symmetrical macrocyclic diketones. 20

Another object of the invention is to provide a process for the production of 8-cyclohexadecen-1-one from 1,9-cyclohexadecanedione.

Still another object of the invention is to provide a process for the production of 9-cyclooctadecen-1-one from 1,10-cyclooctadecanedione. 25

Other objects of the invention will in part be obvious and will in part appear hereinafter.

The invention accordingly comprises the process involving the several steps and the relation and the order of one or more of such steps with respect to each of the others which are exemplified in the following detailed disclosure, and the scope of the application of which is indicated in the claims.

For a fuller understanding of the nature and objects of the invention, reference should be had to the following detailed description.

Civetone or 9-cycloheptadecen-1-one of the following structure

is a naturally occurring substance secreted by the civet cat. Due to its characteristic musk-like odor, it is of exceptional value to the perfume industry as a perfume base and fixative. Homologs of civetone having from 14 to 18 ring members also possess a musk-like odor very similar to that of the naturally occurring civetone. 45 Although there are described in "Chemistry of Carbon Compounds," E. H. Rodd, ed., New York, Elsevier Publishing Company, 1953, volume II, part A, pages 277-284, several syntheses for the perfumery fixative civetone, little attention has been given to the synthesis of civetone homologs such as 7-cyclotetradecen-1-one, 8-cyclohexadecen-1-one and 9-cyclooctadecen-1-one. One method for producing these civetone homologs, described in Swiss Patent 135,921 (1928) and U. S. Patent 1,873,154, involves the pyrolysis of the appropriate dibasic acids. This method is not particularly attractive as the yields of the macrocyclic monoketones are quite low and the syntheses of the requisite unsaturated dibasic acids are lengthy.

The present invention is directed to the production of macrocyclic monoketones in good yields from symmetrical macrocyclic diketones. The process of the present invention comprises partially reducing a symmetrical macrocyclic diketone to the corresponding cyclic hydroxyketone and dehydrating the cyclic hydroxyketone obtained to the desired macrocyclic unsaturated mono-

2

ketone. In one preferred embodiment of the invention, the reaction proceeds as follows:

where n and n_1 are whole numbers of from 6 to 8 and where n and n_1 are numerically equal. In another embodiment, the preferred symmetrical macrocyclic diketones are 1,9-cyclohexadecanedione and 1,10-cyclooctadecanedione, and the civetone homologs produced therefrom are 8-cyclohexadecen-1-one and 9-cyclooctadecen-1-one respectively. The symmetrical macrocyclic diketones employed as starting material in the present invention may be prepared according to the methods described in U. S. Patent 2,584,664.

Specific detailed methods of practicing the present invention are set forth in the following non-limiting examples.

Example I

An acetic acid solution of 0.503 gram of 1,9-cyclohexadecanedione was hydrogenated in a semi-micro apparatus, using 70 milligrams of prereduced Adams catalyst (finely divided platinum produced by the reduction of platinum oxide), until about 104 percent of one equivalent of hydrogen had been absorbed. After separation of the catalyst and removal of the acetic acid in vacuo, the residual solid was treated with about 60 milliliters of hexane at room temperature. There was obtained 0.07 gram of crude 1,9-cyclohexadecenediol which was insoluble in hexane. Cooling the filtered hexane solution to 0°-5° C. gave 0.22 gram of 9-hydroxycyclohexadecanone. The remaining hexane solution was then placed on a magnesium-celite column. Elution with a pentane-benzene mixture gave 0.09 gram of the starting material, 1,9-cyclohexadecanedione. Elution with a chloroform-benzene mixture gave an additional 0.09 gram of 9-hydroxycyclohexadecanone as fine fluffy needles. After recrystallization, the cyclic hydroxyketone obtained had a melting point of 76°-77° C. The total quantity of 0.31 gram of 9-hydroxycyclohexadecanone produced represented a 61 percent yield.

The above reaction proceeded as follows:

A mixture of 170 milligrams of 9-hydroxycyclohexadecanone and 1.5 grams of potassium hydrogen sulfate was heated for about 5 minutes at about 250° C. The resulting mixture was cooled and extracted with pentane. Evaporation of the pentane solution gave a residual oil having an intense musk odor. On cooling, this liquid solidified. About 145 milligrams of 8-cyclohexadecen-1-one with a melting point of 17°-22° C. were obtained. This represented a yield of about 80 percent.

The above reaction proceeded as follows:

Example II

An acetic acid solution of 0.81 gram of 1,10-cyclohexadecanedione was partially hydrogenated using the procedure described in Example I. After separation of the catalyst and removal of the acetic acid, the residue

was dissolved in hexane and placed on an alumina column. Elution with a hexane-heptane mixture gave 0.23 gram of unreduced 1,10-cyclohexadecanedione. Elution with a hexane-benzene mixture gave 0.23 gram of 10-hydroxycyclooctadecanone. Final elution with chloroform also gave 0.16 gram of 1,10-cyclooctadecanediol. After recrystallization from pentane, the cyclic hydroxyketone obtained had a melting point of 80°-81° C.

The above reaction proceeded as follows:

155 milligrams of 10-hydroxycyclooctadecanone were fused with 2 grams of potassium hydrogen sulfate using the procedure described in Example I. Crude 9-cyclooctadecen-1-one was obtained directly from the fused mixture by sublimation. After resublimation, 95 milligrams of 9-cyclooctadecen-1-one were obtained as a waxy solid with a melting point of 40°-41° C. This material had a musk odor similar to that of cyclooctadecanone. The total quantity of 9-cyclooctadecen-1-one obtained represented a yield of 66 percent.

This reaction proceeded as follows:

The above process is also applicable to the production of 7-cyclotetradecen-1-one from 1,8-cyclotetradecanedione.

The partial reduction of the symmetrical macrocyclic diketones having from 14 to 18 ring members (12 to 16 methylene groups between the keto groups) may be achieved in many alternative ways other than through the use of Adams catalyst in acetic acid. For example, Raney nickel, palladium on charcoal, nickel on kieselguhr, copper chromite, platinum or palladium on various other well-known supports may also be used as catalysts. The above catalysts are used typically in solvents such as ethanol, ethyl acetate, acetic acid and the like.

Conditions of reaction such as temperature, pressure, use of solvents, etc., depend on the particular hydrogenation method employed. The hydrogenation must be closely controlled so that but one ketone group of the cyclic diketone employed is reduced to a secondary alcoholic grouping. Complete hydrogenation of the cyclic diketone is undesirable since it produces cyclic diols. For instance, the complete hydrogenation of 1,9-cyclohexadecanedione or 1,10-cyclooctadecanedione results in 1,9-cyclohexadecenediol and 1,10-cyclooctadecanediol respectively.

The partial reduction of the preferred diketones results in symmetrical hydroxyketones having the same number of ring members as the starting material from which it was produced. Thus the number of methylene groups (CH_2) between the hydroxy group and keto group of the hydroxyketone are equal to the number of methylene groups between the two keto groups of the starting material.

The dehydration of the symmetrical macrocyclic hydroxyketone may also be achieved by additional methods other than through the use of potassium hydrogen sulfate. For example, the dehydration may be accomplished by heating the hydroxyketone with sulfuric, phosphoric, formic, oxalic or sulfonic acids or with reagents such as fused zinc chloride, iodine and the like or by passing the vapors of the hydroxyketones over substances such as alumina, thoria, titania, aluminum silicates and the like at suitable temperatures. Conditions of reaction for the

dehydration such as temperatures, use of solvents and the like depend upon the particular dehydration method employed.

The dehydration of the preferred hydroxyketones results in unsymmetrical unsaturated monoketones which, however, contain the same number of ring members as the diketone and hydroxyketone from which they are obtained. The preferred macrocyclic unsaturated monoketones, having from 14 to 18 ring members but containing one less methylene group between the functional groups than are present between the functional groups of the symmetrical cyclic diketone or hydroxyketone, possess the valuable musk odor.

Although specific separation techniques were illustrated in the examples, it should be pointed out that the use of other solvents and separation techniques may be employed in the recovery of either the hydroxyketone or the unsaturated monoketone.

Since certain changes may be made in the above process without departing from the scope of the invention herein involved, it is intended that all matter contained in the above description shall be interpreted as illustrative and not in a limiting sense.

What is claimed is:

25. 1. A process for the production of civetone homologs which comprises the steps of partially reducing a symmetrical macrocyclic diketone selected from the group consisting of 1,8-cyclotetradecanedione, 1,9-cyclohexadecanedione and 1,10-cyclooctadecanedione to the corresponding symmetrical macrocyclic hydroxyketone and dehydrating said symmetrical macrocyclic hydroxyketone to a macrocyclic unsaturated monoketone of the general formula

where n and n_1 are whole numbers of from 6 to 8 and where n and n_1 are numerically equal.

40. 2. A process for the production of civetone homologs which comprises the steps of partially reducing 1,9-cyclohexadecanedione to 9-hydroxycyclohexadecanone and dehydrating said 9-hydroxycyclohexadecanone to 8-cyclohexadecen-1-one.

45. 3. A process for the production of civetone homologs which comprises the steps of partially reducing 1,10-cyclooctadecanedione to 10-hydroxycyclooctadecanone and dehydrating said 10-hydroxycyclooctadecanone to 9-cyclooctadecen-1-one.

50. 4. A process for the production of civetone homologs which comprises the steps of partially reducing 1,8-cyclotetradecanedione to 8-hydroxycyclotetradecanone and dehydrating said 8-hydroxycyclotetradecanone to 7-cyclotetradecen-1-one.

55. 5. A process for the production of macrocyclic unsaturated monoketones which comprises the steps of partially reducing a macrocyclic diketone to the corresponding macrocyclic hydroxyketone and dehydrating said macrocyclic hydroxyketone to a macrocyclic unsaturated monoketone having one less methylene group between the unsaturation and keto group than is present between the keto groups of said macrocyclic diketone.

60. 6. A process for the production of macrocyclic unsaturated monoketones which comprises the steps of partially reducing a symmetrical macrocyclic diketone to the corresponding symmetrical macrocyclic hydroxyketone and dehydrating said symmetrical macrocyclic hydroxyketone to an unsymmetrical macrocyclic unsaturated monoketone.
